CLAIM

The ornamental design for a portion of a video game controller, as shown and described.

DESCRIPTION

FIG. 1 is a top plan view of a portion of a video game controller showing our new design;

FIG. 2 is a top front perspective view thereof;

FIG. 3 is a top left perspective view thereof;

FIG. 4 is a top right perspective view thereof;

FIG. 5 is a top rear perspective view thereof;

FIG. 6 is a bottom plan view thereof;

FIG. 7 is a front elevational view thereof; and,

FIG. 8 is a rear elevational view thereof.

The features shown in broken lines are for illustrative purposes only and form no part of the claimed design.

Our new design of a portion of a game controller is characterized by a guitar shaped body.
